(57) **CLAIM**

An ornamental design for an automatic injector, as shown and described.

DESCRIPTION

FIG. 1 is an isometric view showing the top left distal end of our new design for an automatic injector.

FIG. 2 is an isometric view showing the top right side of the proximal end thereof.

FIG. 3 is an isometric view showing the bottom, right side of the proximal end thereof.

FIG. 4 is a distal end elevation view thereof.

FIG. 5 is a proximal end elevation view thereof.

FIG. 6 is a left side elevation view thereof.

FIG. 7 is a right side elevation view thereof.

FIG. 8 is a top plan view thereof; and,

FIG. 9 is a bottom view thereof.

The dash dot lines immediately adjacent to the shaded areas in FIGS. 1 and 4 represent the boundaries of the claimed design. The dashed lines in the figures illustrate the portions of the design that form no part of the claimed design. None of the broken lines form any part of the claimed design.
